UNITED STATES PATENT OFFICE

2,614,540

FLUID OPERABLE MOTOR EMBODYING AN-
NULAR SERIES OF OPPOSED COAXIAL
CYLINDERS AND PISTONS

James E. Morton, Abilene, Tex.

Application August 9, 1946, Serial No. 689,605

3 Claims. (Cl. 121—119)

1

The invention relates to motors operable by fluid under pressure.

One object of the invention is to provide a motor which includes a shaft and a series of cylinders with pistons therein which are slidable on axes parallel with the shaft and which is adapted for delivering high torque for driving purposes.

Another object of the invention is to provide a motor of this type which includes annular series of opposed pairs of cylinders with pistons slidable on axes parallel with the axis of the shaft, and crank elements between the opposed pistons for delivering high torque to the shaft.

Another object of the invention is to provide a motor of this type which is compact, can be economically fabricated, and is efficient in operation.

Other objects of the invention will appear from the detailed description.

The invention consists in the several novel features hereinafter set forth, and more particularly defined by claims at the conclusion hereof.

In the drawings:

Fig. 1 is a central, vertical, longitudinal section of a motor exemplifying the invention.

Fig. 2 is a transverse section taken on line 2—2 of Fig. 1.

Fig. 3 is a transverse section taken on line 3—3 of Fig. 1.

Fig. 4 is a section through one of the crank-elements and the pinion driven thereby, the pistons being shown by dotted lines.

Fig. 5 is a plan of one of the crank-elements with the roller being illustrated in dotted lines.

Fig. 6 is a transverse section through one of the rings or annuli which are provided with annular conduits for delivering fluid to and from the motor.

Fig. 7 is a side elevation of one of the driven valve members which is provided with ports for controlling the flow of fluid between the cylinders and the conduits in the annuli.

Fig. 8 is a section taken on line 8—8 of Fig. 7.

Fig. 9 is a longitudinal section illustrating a portion of the motor taken through a pair of opposed cylinders and illustrating the pistons in their mid-stroke positions, parts being shown in elevation.

Fig. 10 is an outer side elevation of a portion of one of the heads of the casing.

Fig. 11 is a side elevation of the body of the casing in which the cylinders are formed.

Fig. 12 is a section of the casing body and the conduit rings, taken on line 12—12 of Fig. 11.

2

Fig. 13 is a similar section taken on line 13—13 of Fig. 11.

The invention is exemplified in a motor which comprises a casing which includes a one-piece body section 20, to the sides of which are secured, for example by screws 25, heads 22 and 24. The casing may be supported by brackets 26, which are provided with annular members 28, which are secured by screws 30, to the heads. A shaft 32 extends through head 22, longitudinally into the casing, and is journaled in anti-friction bearings 34 in the heads 22, 24. A cap 36 secured by screws 37 to head 24 encloses the end of shaft 32 which terminates in the casing. A ring 38 is secured to the outer face of head 22 and is provided with an oil seal 39 around shaft 32. This forms a casing which is adapted to retain oil, for lubricating the running parts.

An annular series of cylinders 40, symmetrically disposed around the axis of and having their axes parallel to the axis of shaft 32, are formed in one side portion of casing body 20 and another annular series of cylinders 41, having their axes parallel to the axis of shaft 32, are symmetrically disposed in the other side portion of casing body 20. Each of the cylinders 40 is co-axial with and is disposed in, opposed relation to a cylinder 41. Pistons 42 are slidable in cylinders 40 and pistons 43 are slidable in cylinders 41. The inner ends of cylinders 40, 41, terminate at a radially cylindrical chamber 46. This arrangement of cylinders and pistons exemplifies a motor with annular series of co-axially opposed cylinders which are provided with pistons which are slidable longitudinally of and parallel to, the axis of the shaft 32, so that each pair of opposed pistons will operate a crank-element as hereinafter set forth.

A series of crank elements corresponding to the number of cylinders in each series are provided. Each crank-element is operable by a pair of opposed pistons 42, 43, and is disposed in the casing body 20, between the opposed cylinders 40, 41. Each crank element comprises a bearing member 48 which is journaled in an anti-friction bearing 49, which is mounted in the inner end of the cylindrical chamber 46; an integral eccentric or wrist pin 50, and a roller 52, which is provided with a bushing 53, which is journaled on pin 50; a retaining collar 54 which is held by a split ring 55 on pin 50, and holds the roller on the bearing member 48 of the crank element. The periphery of each roller 52 engages a pair of opposed pistons 42, 43, so that during the operation of one of the opposed pistons by fluid

under pressure acting to drive the roller 52, the opposed piston will be shifted by the roller to discharge the fluid from the cylinder in which it is slideable. This exemplifies a structure in which crank elements which are mounted to rotate on a radial axis are drivably engaged by opposed pistons which are slideable longitudinally and parallel with the axis of shaft 52.

Each crank element is adapted to drive a bevel pinion 58, the outer end of which is secured by a key 49 in the cylindrical bearing member 48. The inner end 59 of each pinion is journalled in an anti-friction bearing 60, which is mounted in an annular member 62, which is integrally formed with and connected by spokes 63, to the annular portion of the casing body 20. Pinions 58 mesh with a bevel gear 64, the hub of which extends through ring 62 and is secured by a key 65 to shaft 32. This exemplifies gearing including radially extending pinions which are driven by the crank elements, for driving shaft 32. The outer ends of the cylindrical chambers 46, in which the crank rollers operate, are each closed by a cap 47, which is removably secured to casing body 20 by screws, for access to the crank elements and their assembly with the casing.

The means for delivering fluid to and exhausting it from cylinders 40 comprises: an annulus or ring 66 and the means for delivering fluid to and exhausting it from cylinders 41, includes a similar annulus or ring 68, both of which fit the inner periphery of the cylindrical portion of the casing body 20 and are fixed therein against rotation. Annular conduits 70 and 71 are formed in ring 66 and annular conduits 72 and 73 are formed in ring 68. Conduit 70 is communicatively connected by a duct 76 (Fig. 12) with a pipe 77 which is secured in the casing body 20. Conduit 71 is communicatively connected by a duct 78 (Fig. 13), to a pipe 79. One of these conduits and pipes is adapted to deliver fluid under pressure to one of the conduits in ring 66, and the other pipe is adapted to exhaust fluid from the other conduit in said ring. Conduit 72 (Fig. 13) is communicatively connected by a duct 80 to a pipe 81, which is connected to casing body 20, and conduit 73 (Fig. 12) is communicatively connected by a duct 82, with a pipe 83. One of the pipes 81 or 83 is adapted to deliver fluid to one of the conduits in ring 68, and the other is adapted to exhaust fluid from the other pipe.

A member 86 is fixedly secured in the casing body 20 in, and closes, the outer end of each cylinder 40, and limits the outward movement of piston 42. A similar member 87 is secured in the casing body 20, in the outer end of each cylinder 41. A port 90 extends from the inner periphery of ring 66, through said ring, and angularly through body 20, to a recess 91 in stop member 86, for conducting fluid between each cylinder 40 and the inner periphery of ring 66. A similar port 92 extends from the inner periphery of ring 68, to a recess 93 in stop member 87. Each of the ports 90, 92, functions to alternately deliver fluid to and exhaust it from the cylinder to which it is connected.

The alternate flow of fluid under pressure, to each cylinder 40 from one of the conduits 70 or 71 in ring 66, and the exhaust of fluid from each cylinder 40 to the other of said conduits, is controlled by a rotary valve member 94, which is secured by key 65 to shaft 32, and has an outer cylindrical periphery fitting the inner periphery of ring 66. The alternate flow of fluid under pressure to each cylinder 41 from one of the conduits 72 or 73, and the exhaust of fluid from each

of said cylinders to the other of said conduits, is controlled by a valve member 96, which has a cylindrical outer periphery fitting the inner periphery of ring 68 and is also fixedly secured to shaft 65. Radial ports 98, one for each cylinder 40, extend between conduit 70 and the inner periphery of ring 66. Ports 99, one for each cylinder 40, connect conduit 71 and the inner periphery of ring 66. Each group of ports 90, 98 and 99, is longitudinally aligned at the inner periphery of ring 66. Ports 100, one for each cylinder 41, connect conduit 72 and the inner periphery of ring 68, and ports 101, one for each cylinder 41, connect conduit 73 and the inner periphery of ring 68. Each group of ports 92, 100 and 101, are longitudinally aligned at the inner periphery of ring 68.

The cylindrical outer periphery of each of the valve members 94, 96, is provided with a series of longitudinally extending channels 104, and with an alternately arranged series of longitudinal channels 105, for controlling the flow of fluid to and from the annular series of cylinders, respectively. The channels 104 in valve member 94 control the flow, in one direction, of fluid between cylinders 40 and one of the conduits 70 or 71, and channels 105 alternately control the exhaust of fluid from said cylinders to the other of said conduits. Similarly, the channels 104 in valve member 96, control the flow of fluid from one of the conduits 72 or 73, to cylinders 41, and channels 105 alternately control the exhaust of fluid from said cylinders to the other of said conduits.

Channels 104, 105, in valve members 94, 96, co-act with the ports in rings 66, 68, respectively, to deliver and exhaust fluid from the cylinders in each annular series, in rotative succession. The series of channels 104, 105, in valve members 94 and 96, respectively, are relatively positioned to deliver fluid for imparting a power stroke to a piston in one annular series of cylinders and exhausting fluid from the co-axially opposed cylinder in the other series, so that while a power stroke is being imparted to one of a pair of opposed pistons, the crank roller between said pistons will impart an exhaust stroke to the other of said pair of pistons. The motor is reversible, depending upon the fluid connections of pipes 77, 79, and 81, 83.

The operation of each pair of pistons 42, 43, in a pair of opposed cylinders 40, 41, will be as follows: assuming pipes 77, 81, are connected to a source of fluid under pressure and pipes 79, 83, are connected for exhausting fluid, fluid under pressure will flow from pipe 77, through duct 76, into conduit 70, and from pipe 81 through duct 80 into duct 72, and fluid from conduit 71 will be exhausted through duct 78, to pipe 79, and from conduit 73, through duct 82, to pipe 83. As a channel 104 registers with longitudinally aligned ports 90, 98, in ring 66, fluid under pressure will flow from conduit 70, said port 98, said channel 104, and port 91, into the cylinder 40 connected to said port 98, and impart a power stroke to the piston 42 in said cylinder. Simultaneously, a channel 105 in valve member 96, will rotate into registry with ports 101 and 92, in ring 68, for exhausting fluid from the opposed cylinder 41, through said port 92, said channel 105, and said port 101, to conduit 73. This will cause piston 42 to impart a power stroke of approximately 180° to the roller 52 and its crankpin 59 between said opposed pair of pistons while piston 43 will be shifted by said roller to exhaust

fluid from said cylinder 41, through its port 92, said channel 105 in valve member 96, and said port 101, to conduit 73, as illustrated in Fig. 8. When the piston 42 has completed its power stroke and the opposed piston 43 has completed its exhaust stroke, a channel 104 in ring 68, will register with aligned ports 101 and 92 for said cylinder 41, and fluid under pressure will be delivered from conduit 72, through said port 100, said channel 104, and said port 92, to said cylinder 41, for imparting a power stroke to said piston 43. Simultaneously, a channel 105 in valve member 94, will rotate into registry with port 99 in ring 66, and its associated port 90, for exhausting fluid from the opposed cylinder 40, to conduit 71, during the power stroke of piston 43. In like manner, the pistons in each pair of opposed cylinders will be operated in rotative succession, to operate the crank rollers 52. The operation of crank rollers 52 will drive pinions 58, which will drive shaft 32 through gear 64.

In the exemplifications of the invention shown, the motor is provided with nine pairs of opposed cylinders and pistons, and a longitudinally aligned group of ports 90, 98, 99, for each cylinder 40, and a similar group 92, 100, 101, for each cylinder 41. The outer periphery of each of the rotatable valve members 94, 96, is provided with ten alternately arranged pairs of longitudinal channels 104, 105. This exemplifies valve means which causes power strokes in rotative succession in both series of opposed pistons and an exceptionally even flow of power and the delivery of enormous torque to the shaft 32. In the exemplification illustrated, the nine crank-pins are angularly positioned to rotate in 40° succession, and each roller and crank-pin receives ten power strokes in opposite directions, during each revolution of shaft 32 and valve members 94, 96. This results in high torque and smooth operation of the motor, without objectionable vibration.

By supplying fluid under pressure, to pipes 79 and 83, and connecting pipes 77 and 81, for the exhaust of fluid, the motor will operate in reverse direction. If pipes 77 and 79, 81 and 83, are closed, to prevent the flow of fluid to the motor and its exhaust therefrom, the fluid will be locked in the cylinders so that the shaft 32 will also be locked against rotation.

An oil duct 110 is provided in each crank-pin 50, which permits oil in the casing to flow to a groove 111, through which oil is delivered to the outer ends of the pinions 58, for lubricating them. An oil duct 112 leads from duct 110, to the bushing 53, for lubricating the bearing surfaces between said bushing and crank-pin 50.

The removable heads 47 provide for access to the chambers 46, in which the crank rollers are operated. The members 86 and 87, in the outer ends of the cylinders, are removable for replacement, by removal of the heads 22, 24. A characteristic of the casing is, that both series of cylinders are formed in a one-piece casing body.

The invention exemplifies a motor operable by fluid under pressure, which is adapted to develop a high and constant torque without vibration; and includes opposed pistons for operating each crank element, which is mounted for sliding movement parallel with the axis of the output shaft.

The invention also exemplifies a motor operable by fluid under pressure, which is compact and simple in construction, can be economically fab-

ricated, and which can be readily assembled and disassembled.

The invention is not to be understood as limited to the details described, since these may be modified within the scope of the appended claims without departing from the spirit or scope of the invention.

Having thus described the invention, what I claim as new and desire to secure by Letters Patent is:

1. A motor operable by fluid under pressure, comprising: a casing including an annular member and sides, a shaft extending into and journaled in the casing, annular series of co-axial opposed cylinders in opposite sides of the casing, having axes substantially parallel with the axis of the shaft, the inner ends of one series of cylinders being spaced from the inner ends of the other series, pistons axially slidable in the cylinders, respectively, individual cranks, each carrying an element engaging the inner ends of opposed pistons, said cranks being disposed substantially at the longitudinal center of the casing, means on the central portion of the annular member of the casing for rotatably supporting the cranks; rings fixed at opposite sides of the casing, each provided with annular intake and outlet conduits for one series of cylinders; valve members in the rings rotatable with the shaft, provided with ports for controlling fluid to and from the cylinders; and means for driving said shaft from the cranks, disposed between the rings and said valve members.

2. A motor operable by fluid under pressure, comprising: a casing including an annular member and sides, a shaft extending into and journaled in the casing, annular series of co-axial opposed cylinders in opposite sides of the casing, having axes substantially parallel with the axis of the shaft, the inner ends of one series of cylinders being spaced from the inner ends of the other series, pistons axially slidable in the cylinders, respectively, individual cranks, each carrying an element engaging the inner ends of opposed pistons, pinions on and co-axially with the cranks, said cranks and pinions being disposed substantially at the longitudinal center of the casing; means on the central portion of the annular member of the casing for rotatably supporting the cranks and the pinions, rings fixed at opposite sides of the casing, each provided with annular intake and outlet conduits for one series of cylinders; valve members in the rings, rotatable with the shaft, provided with ports for controlling fluid to and from the cylinders; and means for driving said shaft from the pinions, and disposed between the rings and said valve members.

3. A motor operable by fluid under pressure, comprising: a casing including an annular member and sides, a shaft extending into and journaled in the casing, annular series of co-axial opposed cylinders in opposite sides of the casing, having axes substantially parallel with the axis of the shaft, the inner ends of one series of cylinders being spaced from the inner ends of the other series, pistons axially slidable in the cylinders, respectively; individual cranks, each carrying an element engaging the inner ends of opposed pistons, pinions on and co-axially with the cranks, said cranks and pinions being disposed substantially at the longitudinal center of the casing, means on the central portion of the annular member of the casing for rotatably sup-

porting the cranks and the pinions, rings fixed at opposite ends of the casing, each provided with annular intake and outlet conduits for one series of cylinders; valve members in the rings, rotatable with the shaft, provided with ports for controlling fluid to and from the cylinders; and a gear disposed between the rings and the valve-members, meshing with said pinions and fixed to the shaft.
